UNITED STATES PATENT OFFICE.

WRAY FALWELL, OF FITCHBURG, MASSACHUSETTS, ASSIGNOR TO EMERSON W. BAKER, OF FITCHBURG, MASSACHUSETTS.

AIR-REGULATING ATTACHMENT FOR CARBURETORS.

Application filed November 5, 1923. Serial No. 672,966.

To all whom it may concern:

Be it known that I, WRAY FALWELL, a citizen of the United States, residing at Fitchburg, in the county of Worcester and 5 Commonwealth of Massachusetts, have invented a new and useful Improvement in an Air-Regulating Attachment for Carburetors, of which the following, together with the accompanying drawings, is a specification.

The present invention relates to an air regulating attachment for carburetors, and is designed for use especially with those types of carburetors which are devoid of 15 air control devices, i. e., carburetors such as are in general use on Ford cars and many other motor vehicles.

The present invention contemplates an air control device which can be operatively 20 associated with such a carburetor with the greatest ease and facility, and with no necessity for the use of special fittings or any attaching device whatsoever. The invention also contemplates a device of this 25 class which, by its construction, absolutely insures against the possibility of error in its positioning, and which, by its construction, furthermore is not subject to damage or breakage in the event of back-firing by 30 the engine. The above and other objects are obtained by the novel construction hereinafter described and claimed, reference being had to the accompanying drawings, wherein—

Fig. 1 is a side elevation, partly in section, showing my improved device in operative association with a carburetor of the type used on Ford and other engines.

Fig. 2 is an enlarged view in side elevation 40 of said device or attachment.

Fig. 3 is a developed view of the blank from which said device is preferably made.

Fig. 4 is a vertical sectional view on the line 4—4 of Fig. 2.

Fig. 5 is a top plan view of my device or attachment.

Like reference characters refer to like parts in the different figures.

Referring first to Fig. 1, the carburetor 50 1, of ordinary and well known construction, is shown in connection with the inlet manifold 2 of an internal combustion engine, and the air supply for said carburetor is shown as being delivered thereto by means of a pipe 3, the latter having its entrance 4 flared

to extend over a portion of the exhaust manifold 5, so that the air supply is suitably heated before delivery to the carburetor. The hot air pipe or fitting 3 is here shown as of the type that is universally used with 60 carburetors of Ford engines, there being a right angle bend in said pipe, as indicated at 6, Fig. 1, which is advantageously utilized in my invention, as hereinafter described.

The attachment which forms the subject matter of my invention is preferably made from a sheet metal blank or stamping of the form indicated in Fig. 3, the same comprising an annular portion 7 having four projecting radial wings 8, 8, with a connected tongue 9 extending from each of said wings. Two of said wings 8, 8, lying oppositely to each other, are bent or pressed upwardly, and the other two are bent or pressed downwardly, all of said wings in this operation being curved so as to constitute arcs of a cylinder whose outside diameter corresponds substantially to the inside diameter of the pipe 3. With the wings thus bent and curved, the blank of Fig. 3 assumes the form of a skeleton cylinder, as shown in Fig. 2, the annular portion 7 constituting a transverse dividing partition in said cylinder, and the wings 8, 8 constituting the cylinder walls proper, as will be readily understood. The tongues 9, 9 of said wings are bent over toward each other at right angles, and the apertures 10, 10 of their overlapping portions thus come into registry to provide bearings for a spindle 11, whose ends, after insertion of said spindle, are upset or enlarged to prevent endwise displacement thereof.

The spindle 11 carries a circular valve member 12 which is free to slide longitudinally on said spindle, and which normally is maintained midway of the skeleton cylindrical casing, in the opening 13 of transverse partition 7, by springs 14, 14 on opposite sides thereof, encircling said spindle and confined between said valve and the tongues 9, 9 at either end. The opening 13 is of greater diameter than valve 12 and hence, even in this centered position of the valve, there is always an annular passage between it and the inner periphery of the partition; as hereinafter described, the area of this passage varies with the suction produced by the engine, when the attachment 100 105 110

is operatively associated with the carburetor.

Such operative association is accomplished simply by removing the usual hot air pipe 5 or fitting 3, and by inserting the attachment into the flared entrance 4, whence it drops to the bottom of the vertical leg of said pipe, coming to rest at the right angled bend 6. Thereupon, the pipe or fitting 3, with the 10 attachment of my invention inserted therein, is replaced on the engine, in the usual relation to the carburetor. No special fittings or attaching devices of any kind whatsoever are required, since the attachment, once inserted, seeks and retains its proper position by the action of gravity alone. Moreover, it is impossible to get the attachment inserted in any but the correct way, since the valve mechanism is double-acting, and the springs 15 work in the same way from both sides thereof. With the attachment in place, the amount of heated air supplied to the carburetor is automatically regulated by the suction, and by the use of the device the 20 motor vehicle can be throttled down to a very slow speed on high gear, and it has also been found that the vehicle when using this device can be started easier in cold 25 weather and can be more readily accelerated than otherwise. A material saving of fuel 30

is also effected. As the suction increases, the valve 12 is automatically shifted and, by moving away from the partition 7, increases the opening for the passage of air to the carburetor. In the event of the engine 35 back-firing, no damage or breakage can occur, since the pressure operating on the valve is cushioned by the outer spring 14.

I claim—

1. As a new article of manufacture, an 40 air regulating attachment for a carburetor, comprising a double-acting yielding check member offering the same resistance to air in either direction insertible either end foremost in a vertical leg of the hot-air supply 45 tube leading to said carburetor.

2. As a new article of manufacture, an air regulating attachment for a carburetor, comprising a casing of skeleton cylindrical form providing a central partition and made 50 from a single stamping, the latter having oppositely bent wings, with inturned tongues on said wings to provide bearings at each end of said casing for a spindle running longitudinally of said casing, and said 55 spindle having thereon, in the vicinity of said partition, a slidable valve member subject to spring pressure on both sides.

WRAY FALWELL.
